UNITED STATES PATENT OFFICE

SAMUEL T. SHERRICK, OF DENVER, COLORADO, ASSIGNOR TO S. & C. HOLDING CORPORATION, OF DENVER, COLORADO, A CORPORATION OF COLORADO

LIQUID FUEL BURNER

Application filed March 28, 1932. Serial No. 601,543.

This invention relates to a liquid fuel burner and has for its principal object, the provision of a highly efficient burner for liquid fuels which can be employed either as a complete self contained unit, or in connection with a permanent fuel supply.

Another object of the invention is to so construct the device that vapors from the fuel reservoir will be fed into the burner flame when it has reached a pre-determined pressure.

A further object is to provide a burner in which a supply of liquid fuel will be brought to a high temperature in the reservoir before being fed to the burner.

A still further object is to provide means whereby an auxiliary oxygen supply may be fed to the burner flame should an exceedingly high temperature be desired.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a vertical section through the improved burner arranged as a self contained unit. The section in this view is taken on the line 1—1, Fig. 2.

Fig. 2 is a plan view of the burner of Fig. 1.

Fig. 3 is a horizontal section therethrough taken on the line 3—3, Fig. 1.

Fig. 4 is a diagrammatic view illustrating the burner connected with a permanent fuel supply, and with an oxygen tank.

Fig. 5 is a detail view illustrating a sealing cap which may be employed to seal the burner of Fig. 1 when not in use.

Fig. 6 illustrates a sectional view through a type of relief valve that may be employed in the invention.

The invention comprises the following construction:

A fuel reservoir 10 is provided with a burn-

er sleeve 11 which projects upwardly from the bottom of the reservoir through the top thereof. An air conduit 12 is positioned within the sleeve 11 and extends downwardly through the bottom of the reservoir 10, thence outwardly terminating in an air intake 13. The reservoir is supported above the air intake 13 on suitable legs 14.

A tubular fuel ring 15 is positioned in the bottom of the sleeve 11. The fuel ring 15 communicates with the reservoir through a needle valve seat 16. The needle valve seat is controlled by means of a needle valve 17, which extends through the wall of the reservoir 10 protected by suitable packing 18.

The space between the air conduit 12 and the sleeve 11 is filled with a suitable porous fire-proof material 19. The particular material which is intended to be used for this purpose will be incorporated in a second application for Letters Patent thereon. Any material, however, which will provide an interconnected series of relatively small voids or cells would be satisfactory for this purpose. The porous material extends from the bottom of the sleeve 11 substantially to the top of the air conduit 12.

The reservoir 10 may be filled through a suitable filler opening by removing a filler cap 20.

When the needle valve 17 is opened, it allows the fluid fuel to flow into the fuel ring 15 and from thence through a series of perforations 21 in the bottom of the ring 15 to the interior of the sleeve 11. It will rise in the sleeve 11 to the liquid level in the reservoir 10, and will thence be carried to the top of the porous material 19 by the absorptive capillary attraction thereof.

The fuel is ignited at the surface of the porous material 19 and the flame will project above the burner sleeve 11. This flame will heat the sleeve 11 and the porous material 19 to a point where the ascending fluid will be vaporized and gassified, so that, thereafter the flame will be supplied with gas.

The hot porous material and the hot sleeve 11 will raise the temperature of the liquid fuel in the reservoir 10 causing it to create a pressure therein which will still further

increase the flow of the fuel oil through the burner. When this pressure reaches a pre-determined point where it might become dangerous, it is relieved through a by-pass pipe 22 and a spring actuated check or safety valve 23. The valve 23 may be of any of the usual designs which admit flow at certain pressures by preventing return flow at all pressures. A typical valve of this type 10 is illustrated in section in Fig. 6. Such valves are readily purchasable on the market and need not be described in detail herein.

The gas from the valve 23 flows into a tubular gas ring 24 secured about the upper 15 extremity of a burner sleeve 11. A series of perforations 25 communicate between the gas ring 24 and the interior of the burner sleeve 20 so that this gas or vapor will be projected into the flame to supply additional fuel thereto. The air supply through the 20 air intake can be controlled as desired by means of a suitable shutter cap 26, the position of which is indicated in broken line at 26.

25 The device as thus far described forms a complete unit which requires no external fuel supply and which is conveniently portable. It makes an excellent camp stove for tourists and the like. The top of the reservoir is 30 provided with a series of supports which can support any desired cooking utensil. For heating purposes it has been found advantageous to place a plate of fire clay or similar heat resisting material upon the supports 27 as indicated at 28. This serves to 35 spread the flame over a relatively large area so as to increase its effectiveness in heating the surrounding air.

40 While being transported, the burner sleeve 11 may be closed by means of a suitable threaded cap 29 which is provided with an internal box 30. When secured upon the upper extremity of the burner sleeve 11, the cap 29 effectively closes the sleeve and the 45 boss 30 seals the air conduit 12 so as to prevent any evaporation from the porous material 19.

50 Where it is desired to use the burner in more permanent installations, and for long periods of time, it can be connected up with a main fuel supply tank, as indicated at 31, in Fig. 4. The connections are made by removing a plug 32 adjacent the bottom of the reservoir 10 and installing a supply pipe 33, controlled by a valve 34, between the reservoir 55 10 and the tank 31. The by-pass pipe 22 is then placed by means of a return pipe 35, controlled by a valve 36, which extends between the by-pass opening in the reservoir 60 10 and the tank 31, as shown in Fig. 2.

65 By this arrangement fresh fuel will be constantly supplied to the reservoir 10 through the supply pipe 33. The vapor pressure in the upper portion of the reservoir 10 may be relieved through the return

70 pipe 35. The returning vapors will be condensed in the reservoir 10 so as not to be lost to the atmosphere. It has been found that a light burner 37 can be connected to the return pipe 35 or the by-pass pipe 22 to employ a portion of the returning gases for lighting purposes, if desired.

75 If the normal temperature of the burner is not sufficiently high for the desired operations, it can be increased by connecting the fuel ring 24 with an oxygen tank 38 by means of a suitable connecting pipe 39. This will supply pure oxygen through the openings 25 directly into the flame, and will bring the 80 temperature of the latter to any desired degree.

85 The invention can be used upon any suitable liquid fuel, and it has been found to be particularly effective when used with low grade alcohol.

90 While a specific form of the improvement has been described and illustrated herein, it is desired to be understood that the same may be varied, within the scope of the appended claims, without departing from the spirit 95 of the invention.

Having thus described the invention, what is claimed and desired secured by Letters Patent is:—

1. A liquid fuel burner comprising: a fuel reservoir; a burner sleeve projecting upwardly from within said reservoir through the top thereof; an air conduit passing upwardly through said burner sleeve in spaced relation to the walls thereof and opening through the bottom of said fuel reservoir; porous material filling the space between said air conduit and said burner tube; and a perforated tubular ring surrounding said air conduit within said burner sleeve, said ring communicating with 100 said reservoir.

105 2. A liquid fuel burner comprising: a fuel reservoir; a burner sleeve projecting upwardly from within said reservoir through the top thereof, an air conduit passing upwardly through said burner sleeve in spaced relation to the walls thereof; porous material filling the space between said air conduit and said burner tube; a perforated, horizontally placed tubular ring in said burner sleeve, said ring communicating with 110 said reservoir; and a valve arranged to control the supply of fuel to said tubular ring, said valve being operable from the exterior 115 of said reservoir.

120 3. A liquid fuel burner comprising: a fuel reservoir, a burner sleeve projecting upwardly from said reservoir; an air conduit passing upwardly through said burner sleeve in spaced relation to the walls thereof, porous material filling the space between said air conduit and said burner tube; means for admitting fuel from said reservoir to said porous material; an annular tube surrounding 125 said burner sleeve, there being openings 130

communicating from said tube through said sleeve; and a by-pass connection from the upper portion of said reservoir to said tube.

4. A liquid fuel burner comprising: a fuel reservoir, a burner sleeve projecting upwardly from said reservoir; means for admitting fuel from said reservoir to said burner sleeve; an annular tube surrounding said burner sleeve and provided with perforations communicating through the wall of said sleeve; a by-pass connection from the upper portion of said reservoir to said tube; and a valve in said by-pass connection arranged to open at a pre-determined pressure.

5. A liquid fuel burner comprising: a fuel reservoir, a burner sleeve projecting upwardly from said reservoir; means for admitting fuel from said reservoir to said burner sleeve; a perforated annular tube surrounding said burner sleeve and communicating therethrough; a by-pass connection from the upper portion of said reservoir to said tube; and a valve in said by-pass connection arranged to open at a pre-determined pressure; and means for supplying oxygen to said annular passage.

In testimony whereof, I affix my signature.

30 SAMUEL T. SHERRICK.
